UNITED STATES PATENT OFFICE

PETER H. RAAP, OF OAK PARK, ILLINOIS, ASSIGNOR TO CENTRAL METALLIC CASKET COMPANY, A CORPORATION OF ILLINOIS

DESIGN FOR A BURIAL CASKET

Application filed July 15, 1932. Serial No. 44,343. Term of patent 14 years.

To all whom it may concern:

Be it known that I, PETER H. RAAP, a citizen of the United States, residing at Oak Park, in the county of Cook and State of Illinois, have invented a certain new, original, and ornamental Design for Burial Casket, of which the following is a specification, reference being had to the accompanying drawing, forming a part thereof.

The figure is a front elevation of a burial casket showing my new design.

I claim:

The ornamental design for a burial casket as shown.

PETER H. RAAP.
